UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

VACUUM-TUBE APPARATUS.

Application filed July 3, 1920. Serial No. 393,813.

To all whom it may concern:

Be it known that I, WILLIAM C. WHITE, a citizen of the United States, residing at Schenectady, in the county of Schenectady, 5 State of New York, have invented certain new and useful Improvements in Vacuum-Tube Apparatus, of which the following is a specification.

My present invention relates to improvements in vacuum tube apparatus, and particularly in the type of apparatus commonly known as electron discharge apparatus.

The object of my invention is to provide a simple, convenient and efficient apparatus 15 for and method of controlling by means of a magnetic field an electron current between two electrodes of an electron discharge device.

In carrying my invention into effect I 20 produce a stream of electrons between a cathode and plate electrode of an electron discharge device and cause the velocity of this stream to be greatly decreased as the electrons approach the plate electrode. By 25 producing a magnetic field in the region adjacent the plate electrode which acts upon these slowly moving electrons, it is possible by means of a comparatively weak magnetic field to produce a substantial variation in 30 the electron current received by the plate electrode.

The novel features which I believe to be characteristic of my invention are set forth with particularity in the appended claims, 35 the invention itself, however, both as to its organization and method of operation, together with further objects and advantages thereof, will best be understood by reference to the following description taken in connection with the accompanying drawing in 40 which Fig. 1 is a view partly broken away of an electron discharge device which may be employed in carrying out my invention; Fig. 2 is a typical characteristic curve showing 45 the relation between the plate current and the strength of the magnetic field, and Fig. 3 is a diagrammatic illustration of a circuit connection which may be employed in carrying my invention into effect.

The electron discharge device illustrated in the drawing comprises an evacuated receptacle 1 containing a filamentary cathode 2, a grid electrode 3 in the form of a helix surrounding the cathode 2, and a plate electrode 4 in the form of a cylinder surrounding the

electrode and grid. In the circuit arrangement indicated in Fig. 3 the battery 5 supplies the heating current for the cathode 2 for heating it to incandescence in order to furnish a supply of electrons for the operation of the device, the variable resistance 6 being inserted for varying the heating current. A battery 7 having its positive terminal connected to the grid 3 furnishes a means for maintaining the grid 3 at a desired positive potential with respect to the cathode whereby the electrons emitted from the cathode will be given a high velocity. A battery 8 may be connected between the cathode and plate electrode 4 for maintaining the plate electrode at a desired potential with respect to the cathode. In some cases this may be positive and in other cases it may be negative, and again this battery may be omitted entirely. In the operation of the device a portion of the electrons emitted from the cathode 2 strike the grid 3 while another portion of them will pass between the turns of the grid 3 and move toward the plate electrode 4. As these electrons approach the plate electrode 4, however, their velocity will greatly decrease because of the fact that the plate 4 is maintained at a potential which is either negative with respect to the cathode, or in the extreme case is only slightly positive with respect to the cathode.

If a magnetic field is set up in the space between the electrodes in a direction parallel to the major axis of the electrodes by passing current through the winding 9 surrounding the receptacle 1, it will be possible to readily control the flow of electrons which reach the plate electrode 4.

It has heretofore been known that it is possible by means of a magnetic field to vary 95 the paths of moving electrons and in this way vary the electron current between the two electrodes. In the operation of this type of device, however, it has been customary in the past to provide an appreciable 100 potential difference between the two electrodes and thereby cause the electrons to move between the two electrodes with a high velocity. Under these conditions a comparatively strong magnetic field is required to 105 produce a sufficient deflection of the electrons to vary the electron current between the electrodes. With the arrangement I have just described, however, it is possible by means of a magnetic field of small inten- 110

sity such as may be produced by means of a weak variable current which it is desired to amplify, to produce appreciable changes in the electron current between the cathode and 5 plate electrode.

The curve of Fig. 2 shows the relation between plate current and the strength of magnetic field in a device such as that I have just described. It is to be observed 10 that a variation in the strength of the magnetic field in either direction produces a corresponding variation in the plate current. It will be noted that the maximum current in this case instead of occurring at 15 zero value of the magnetic field, occurs with a given value of magnetic field in what is indicated as the negative direction. This is due to the fact that the magnetic field set up by the heating current of the cathode acts 20 upon the electrons and tends to deflect them to some extent. As a result of this fact the slope of the characteristic curve at zero value of the magnetic field is such that the device may be operated to advantage at this 25 point. In the case indicated by this characteristic curve, the grid electrode was given a positive potential of forty volts and the plate battery 8 was omitted entirely. In the operation of this device as an amplifier 30 of variable currents the currents to be amplified are supplied to the winding 9 and the amplified current may be observed in a telephone 10 or other suitable indicating device in circuit between cathode and plate electrode. 35

I am aware that it has heretofore been proposed to operate a device of the general construction indicated in the drawing in such a way that secondary electrons will be emitted 40 from the plate electrode 4 in sufficient numbers to produce a negative resistance characteristic between cathode and plate electrode. It has been proposed to vary the value of this negative resistance by 45 means of a magnetic field applied in the manner which I have indicated. In this case, however, it is necessary to cause the electrons to strike the plate electrode with a high velocity in order that secondary 50 electrons may be emitted. As a result, a strong magnetic field is required to produce any appreciable deflection of the electrons. In the operation of the apparatus in the 55 manner which I have described, the electrons are caused to strike the plate electrode with a velocity so low that secondary electrons will not be emitted.

While I have illustrated only one form of 60 device for carrying out my invention and I have indicated in a diagrammatic way a single circuit connection for utilizing my invention, it will be apparent to those skilled in the art that my invention is by no means limited to the particular device or circuit arrangement shown, but that 65

many modifications in the form of the apparatus used as well as in the circuit arrangements employed may be made without departing from the scope of my invention, as set forth in the appended claims. 70

What I claim as new and desire to secure by Letters Patent of the United States, is,—

1. The combination in an apparatus of the class described of an electron discharge device comprising an electron emitting cathode, a grid electrode and a plate electrode, means for producing a high velocity stream of electrons between the cathode and grid electrode, means for producing a stream of electrons which move between cathode and grid at a high velocity and approach the plate electrode with a decreasing velocity, and means for producing a magnetic field in the space between the grid electrode and the plate electrode. 80

2. The combination in an apparatus of the class described of an electron discharge device comprising an electron emitting cathode, a grid electrode and a cylindrical plate electrode surrounding the grid electrode, a source of potential connected in such a way that the grid electrode is rendered positive with respect to the cathode, means for maintaining the plate electrode at a potential lower than that required to produce secondary electron emission therefrom, and means for producing a magnetic field in the space between the grid electrode and the plate electrode. 90

3. Means for amplifying variable currents comprising an electron discharge device having an electron emitting cathode, a grid electrode and a plate electrode, means for producing a stream of electrons which flow from cathode to grid electrode at a high velocity and approach the plate electrode with a much lower velocity, and means for producing by the current to be amplified a magnetic field in the space between the grid electrode and the plate electrode. 100

4. Means for amplifying variable currents comprising an electron discharge device having an electron emitting cathode, a grid electrode and a cylindrical plate electrode surrounding the grid electrode, a source of potential connected in such a way that the grid electrode is maintained positive with respect to the cathode, means for maintaining the plate electrode at a potential lower than that required to produce secondary electron emission therefrom, and means for producing by the current to be amplified a magnetic field in the space between the grid electrode and the plate electrode. 110

5. The method of operating an electron discharge device having an electron emitting cathode, a grid and a plate electrode surrounding the grid electrode which consists in producing a high velocity stream of electrons between cathode and grid elec- 125

trode, causing electrons which pass through the grid electrode to approach the plate electrode with a velocity so low that they will be incapable of producing secondary electrons when they strike the plate electrode, and varying the current between cathode and plate electrode by producing a magnetic field in the space between the electrodes in a direction parallel to the major axis of the electrodes.

6. The method of operating an electron discharge device having electron emitting cathode, a grid and a plate electrode, which consists in producing a stream of electrons which move at high velocity in the space between the cathode and grid electrode, causing the velocity of the electrons which pass through the grid to greatly decrease as they approach the plate electrode, and varying the current between cathode and plate electrode by producing a magnetic field in the space between the electrodes.

7. The method of amplifying a variable current by means of an electron discharge device having an electron emitting cathode, a grid and a plate electrode surrounding the grid electrode which consists in producing a high velocity stream of electrons between

cathode and grid electrode, causing the electrons which pass through the grid electrode to approach the plate electrode with a velocity so low that they will be incapable of producing secondary electrons when they strike the plate electrode, and varying the current between cathode and plate electrode by producing by means of the current to be amplified a magnetic field in the space between the electrodes in a direction parallel to the major axis of the electrode.

8. The method of amplifying a variable current by means of an electron discharge device having an electron emitting cathode, a grid and a plate electrode, which consists in producing a stream of electrons which move at a high velocity between cathode and grid electrode, causing the velocity of the electrons which pass through the grid to greatly decrease as they approach the plate electrode, and varying the current between cathode and plate electrode carried by the electron stream by producing by means of the current to be amplified a magnetic field in the space between the electrodes.

In witness whereof, I have hereunto set my hand this 1st day of July, 1920.

WILLIAM C. WHITE.
